UNITED STATES PATENT OFFICE.

JOHN MCFARLANE AND EDWARD D. STERNE, OF WASHINGTON, DISTRICT OF COLUMBIA, ASSIGNORS OF ONE-HALF TO OBADIAH A. PURDEY, OF WASHINGTON, DISTRICT OF COLUMBIA.

FURNACE.

SPECIFICATION forming part of Letters Patent No. 689,901, dated December 31, 1901.

Application filed April 5, 1901. Serial No. 54,497. (No model.)

To all whom it may concern:

Be it known that we, JOHN MCFARLANE and EDWARD D. STERNE, citizens of the United States, residing at Washington, in the District of Columbia, have invented new and useful Improvements in Furnaces, of which the following is a specification.

Our invention relates to improvements in furnaces; and it consists in the novel features of construction hereinafter described, reference being had to the accompanying drawings, which illustrate one form in which we have contemplated embodying our invention, and said invention is fully disclosed in the following description and claims.

Referring to the drawings, Figure 1 is a vertical cross-section looking from the front of the furnace. Fig. 2 is a vertical cross-section looking from the side of the furnace. Fig. 3 is a plan view of the fire pot and grate, and Fig. 4 is a detail view of the draft-closing plates with a portion of their operating mechanism.

The object of our invention is to provide an improved furnace wherein the draft which would ordinarily pass up through the fuel from below the grate is cut off and allowed to percolate through the fuel from all sides and a very small portion permitted to pass up under the grate.

A further object is attained by our device. After the fire is started and the coal-bed thoroughly heated the draft-closing plates are shut and the draft passes through the openings in the fire-pot and air is thoroughly mixed with the flames from the fuel, thereby making combustion more complete and consuming any smoke which may rise from the fire itself or from fuel thrown on the same.

A represents the brickwork of a furnace. On this brickwork rests the boiler B. Below the boiler, inside the brickwork and secured to suitable angle-irons a, are the fire-pots C C. A space is left between the two fire-pots and also between each fire-pot and the adjacent wall of the brickwork. These spaces are closed at the top to prevent the escape of air for a purpose hereinafter mentioned. The central space c is closed by the plate c', while

the spaces c² c³ are closed by the angle-irons a. 50 The back, front, and two sides of each of these fire-pots are perforated, as shown at a', for a purpose hereinafter described. Stationary grate-bars D are secured at the under edge of the fire-pots C by suitable supports d d', 55 mounted in the brickwork. In the front and back of the furnace are plate-supports E E', in which are pivoted the draft-closing plates F F'. (Shown in Fig. 4 of the drawings.) These draft-closing plates are each swiveled to a 60 short arm f, each of which is in turn swiveled to a rod f² in such a way that all of the plates F are operated in unison thereby. The rod f² extends across the front of the furnace under the grate and out through the brick-work through a suitable opening in the side thereof. A series of these draft-closing plates are arranged beneath each set of grate-bars, as is shown in Fig. 1 of the drawings. The space between the fire-pots is closed at the 70 bottom by a set of secondary draft-plates G, similar to the draft-closing plates. To the under side of these plates G are pivoted short arms g, the lower ends of which are each pivoted to a rod e' in such a manner that the 75 plates G can be operated together to close the space between the fire-pots. This rod g' runs transverse of the furnace beneath the grate and extends through and out beyond the brickwork for a reason which will herein-after appear. 80

The spaces at the sides of the fire-pots adjacent to side walls of the brickwork are adapted to be closed at the bottom by means of the plates L, which have short arms h swiveled to the under side thereof. These short arms are also pivoted to the rod g' and are adapted to be operated therewith. 85

The plates G are so arranged with respect to the plates L that both sets are adapted to 90 be operated by one movement of the rod g'.

A weighted lever f³, fulcrumed at f⁴, is connected with the rod f² at f⁵ and to the rod g' at f⁶. The weight X on the end of this lever f³ tends to normally hold the draft-closing plates 95 F in a closed position and the plates G and L in an open position, the object of which will hereinafter be set forth.

The operation of the device is as follows: A fire is started on the grate, with the draft-closing plates F open to allow the draft to pass up through the fire. When the bed of fuel becomes thoroughly heated, these draft-closing plates are closed and the secondary draft-closing plates G and L simultaneously opened, thus forcing the draft through the spaces between and around the fire-pots. The air then enters the perforations in the said fire-pots and percolates through the fuel, thoroughly mixing air with the gas generated by the fuel, making combustion more complete thereby and consuming any smoke which may rise from the fire itself or from fresh fuel thrown on the same.

We have shown and described our invention as being applied to a stationary boiler; but it may be arranged to operate in connection with marine and locomotive boilers without departing from the spirit of our invention.

Having described our invention, what we claim, and desire to secure by Letters Patent, is—

1. In a furnace, the combination with the combustion-chamber and the grate, of a fire-

pot having its entire surface perforated from the upper to the lower edge thereof, pivotally-mounted plates adapted to shut off the direct draft through the grate, similarly-mounted plates for opening the secondary draft and directing the same through said perforations in said fire-pot, and means for operating both sets of plates simultaneously, substantially as described. 30

2. In a furnace, the combination with the combustion-chamber and the grate, of a fire-pot having its entire surface perforated from the upper to the lower edge thereof, pivotally-mounted plates adapted to shut off the direct draft through the grate, similarly-mounted plates for opening the secondary draft and directing the same through said perforations in said fire-pot, and means for operating both sets of plates, substantially as described. 40

In testimony whereof we affix our signatures in presence of two witnesses.

JOHN McFARLANE.
EDWARD D. STERNE.
